[57] CLAIM

The ornamental design for check holder for key chain,
as shown and described.

DESCRIPTION

FIG. 1 is a front view of a check holder for key chain showing our new design, the rear view being a mirror image of the front view;

FIG. 2 is a right side view thereof, the left side being a mirror image of the right side;

FIG. 3 is a bottom view thereof; and,

FIG. 4 is a top view thereof.

FIG. 1

FIG. 2

FIG. 3

FIG. 4
